UNITED STATES PATENT OFFICE.

EDWARD B. CAMPBELL, OF ST. LOUIS, MISSOURI, ASSIGNOR TO THE WILLIAMS PATENT CRUSHER AND PULVERIZER CO., OF ST. LOUIS, MISSOURI, A CORPORATION OF MISSOURI.

GRINDER.

1,322,532.

Specification of Letters Patent. Patented Nov. 25, 1919.

Application filed May 20, 1918. Serial No. 235,533.

To all whom it may concern:

Be it known that I, EDWARD B. CAMPBELL, a citizen of the United States, residing at St. Louis, State of Missouri, have invented 5 certain new and useful Improvements in Grinders, of which the following is a specification.

This invention relates to certain new and useful improvements in grinders, the peculiarities of which will be hereinafter described and claimed.

The main object of my improvements is to simplify construction, increase the efficiency of the grinder and facilitate adjustment and 15 replacement of the parts.

In the accompanying drawings on which like reference letters indicate corresponding parts, Figure 1 represents a grinder embodying my invention, shown half in front 20 view and half in vertical sectional elevation parallel with the shaft; and Fig. 2 represents a vertical sectional elevation on the line X of Fig. 1.

In the grinder at present considered I 25 have shown the front plate A, the back plate B, and the sides C and also the top cover D as formed in one piece as by casting integrally. The sides have large openings E through which the shaft F with the disks G 30 keyed thereon, which disks carry the hammer rods H that support the pivoted hammers I, constituting the cylinder,—may all be inserted within said housing. It is then adjusted to proper central position with respect to a perforated or other form of cage J.

This cage has heretofore given considerable difficulty when it was desired to remove it, and in this application I have shown a 40 simple and effective method of mounting. In each side is a slot K, arched concentrically with the axis of the housing of the mill, which corresponds with the axis of the shaft when properly mounted in the housing. 45 The said slot extends from the front to the back nearly the half circumference below the horizontal plane through the shaft as shown in Fig. 2. The upper side or edge of said slot constitutes a bearing surface for a cage J and is preferably provided with a flange L on the inside of each housing that extends from the back around upward toward the front and ends below the entrance M at the 50 top of the casing above which is indicated by dotted lines at N the feeder that may be

used with this grinder. The flange widens the bearing edge for the cage and stiffens the side casing. The bottom edge of said slot is preferably beveled from outside inward and upward, so that the cross section of the slot 60 presents a wedge shape opening, in which a correspondingly arched and wedge shape filler piece O is mounted. This filler piece with its wedge shape bottom matching the bottom of the said slot K, and its upper edge 65 flat or otherwise corresponding to the shape of the cage J, acts to support the cage and hold it firmly against the upper side edge of the slot K, with equal radial pressure along the length when the rods P, passing through 70 both filler pieces and below the cage, are tightened. The wedge-shaped filler pieces are drawn toward each other and thus exert a radial pressure slantingly inward toward 75 the cage and uniformly throughout the length of the cage. This arched slot may be on one or both sides, and other means may be employed to hold the cage in its position against the upper edge of this slot.

The end of the cage abuts or ends adjacent to a ledge Q at the front plate near the horizontal plane and connecting the sides C. In the ledge at its upper surface is formed a socket q, preferably semi-cylindrical, and in this socket is mounted the rounded end 80 of an arched breaker plate R, the front of 85 which on the inside is provided with serrations, horizontally disposed, and preferably increasing in size from the lower end upward to the top as shown in Fig. 2. The top 90 of said plate is formed in an arch about the center of the socket end, whereby the plate may be adjusted inward and outward at the top by suitable means, below a cross bar S connecting the sides of the casing and 95 flanged as shown, for strength and the attachment of the feeder before mentioned. The top of said breaker plate extends backward in an apron or flange r and on the arch about the center before mentioned. At 100 the back of the flange are depending hooks T, set a suitable distance away from the sides as shown in Fig. 1, and forming an open slot below the flange r adapted to receive the bent out end U of the threaded rod 105 V, having nuts thereon for adjustment and fastening said rods in a lug W vertically disposed and extending from the side housing inward toward the central plane as shown in Figs. 1 and 2. When the ends U 110

of said rods are positioned horizontally in engagement with the depending hooks T, the breaker plate may be adjusted by varying the location of the jam nuts on the 5 threaded portions of the rods. Fig. 2 shows in dashed lines the drawn outward position of the breaker plate which is required when certain kinds of feed are supplied to the grinder. When the breaker plate has worn, 10 or finer grinding is desired, the top is adjusted inward toward the hammers I; the apron-arched top of the breaker plate thus overhanging the hammers and pivoted bottom end is adapted to deliver the feed from 15 the upper end of the serrated front into direct path of the hammers. The apron and top of breaker plate thus take the place of a slide valve for regulating the size of inlet from the supply hopper above. Drawing 20 the breaker plate outward allows more space for feed to enter from the hopper and also increases the angle between the plate and the path of the hammers. Adjusting the plate inward reduces the supply opening 25 and likewise diminishes the angle between the plate and path of the hammers, and accords with the lesser amount received from the supply hopper. The cross bar S holds the breaker plate in position, but if desired, 30 the bottom end may likewise be engaged at each side by a set screw 2, Fig. 3, tapped through each side and into engagement with the bottom end of said plate. When it is desired to remove the breaker 35 plate, the bent ends U of the adjusting rods are turned downward out of engagement with the hooks T, which allows the top of the breaker plate to swing inward till the apron r is clear of the cross bar S. The 40 dotted line in Fig. 2 shows a recess 3 from the serrated front, and arched to correspond with the ledge L to allow of this forward movement of the breaker plate, which in this position may be readily slipped upward 45 through the feed opening M. This arched breaker plate does not require extreme nicety of fitting at the socket or the apron top but may be ground on the emery wheel where necessary; a tight fit is not necessary

at the sides of the breaker plate and the 50 sides of the housing, as the projecting ledge L acts as a guard to direct the material away from the sides. It will be noticed that the lower end of the breaker plate is practically aligned with the adjacent end of the 55 cage.

I claim:

1. In a machine of the character described, the combination with a casing having a feed opening at the top, of a pivoted 60 breaker plate located below said feed opening and adjustable at the top across said feed opening and overhanging the bottom end and having a flange at the top concentric with the pivot and extending backward 65 outside the feed opening, and inclining downward toward the front to guide and regulate the feed passing through said opening, and means to secure said breaker plate in any rotated position. 70

2. A machine of the character described comprising a casing having a front plate, a horizontal ledge on said plate near the horizontal plane,—said ledge at its upper surface having a semi-cylindrical socket,—a 75 breaker plate having its bottom end rounded to match said socket, and means to adjust said breaker plate rotatably in said socket. 75

3. A machine of the character described comprising a shaft, a concentric cage, a casing having in each side housing an arched slot with a concentric inner side edge engaging said cage and an inwardly beveled outer edge forming a wedge-shaped cross section of slot, a filler piece arched to fit 85 each slot, and having a similar wedge-shaped cross section engaging said cage and beveled outer edge respectively, and cross rods passing below said cage and through said filler pieces, and exerting inward radial 90 pressure along the edges of said cage. 80

In testimony whereof I have affixed my signature in presence of two witnesses.

EDWARD B. CAMPBELL.

Witnesses:
